[57] **ABSTRACT**

Display apparatus in which line symbols are displayed by scanning a CRT in a raster and brightening up portions of the raster lines. The portion of raster line to be brightened-up is defined by a digital output. A cyclic counter produces a large number of pulses during each raster line to notionally divide each line into a number of equal length, sequentially numbered sections changes in the brightness being effected when there is correspondence between the digital output and the counter output.

DISPLAY APPARATUS

This invention relates to display apparatus of the kind in which a display area is scanned in a raster and in which a symbol can be produced on the display area by causing a change in a visual parameter, e.g., brightness, of one or more selected portions of the raster lines.

Accordingly, this invention provides display apparatus of the kind hereinbefore defined comprising means for producing a digital output defining the position of each raster line portion required to be selected to display a desired symbol, means for producing reference signals corresponding to points along each raster line and an output circuit for producing a signal for changing said visual parameter at each selected raster line portion determined by the digital output.

According to a preferred feature, the display apparatus includes a cyclic counter operating in synchronism with the raster line scanning generator such that a large number of pulses occur during each raster line, thereby notionally dividing each raster line into a large number of equal length, sequentially numbered, sections changes in said visual parameter being effected when there is correspondence between the digital output and the output of said counter.

According to a further preferred feature, the display apparatus includes at least one delay circuit for delaying the signal from the output circuit whereby the number of sections into which each raster line is divided is effectively increased without increasing the pulse frequency from the cyclic counter.

According to yet a further preferred feature, the display apparatus includes a circuit for changing the shape of the signal from the output circuit whereby the number of raster lines is effectively increased.

The invention will be more readily understood from the following description of a preferred embodiment in which a line symbol is produced on the screen of a cathode ray tube by brightening up portions of the raster, taken in conjunction with the accompanying drawings in which:

FIG. 1 is a schematic diagram of a cathode ray tube screen showing the parameters defining a line symbol;

FIG. 2 is a block diagram of the display apparatus;

FIG. 3 is a block diagram of the output stage of FIG.

2;

FIG. 4 is a block diagram of the delay circuit of FIG.

2;

FIGS. 5a and 5b show respectively the optimum and actual shapes of bright-up pulses applied to the cathode ray tube under certain conditions of operation of the apparatus, and

FIG. 6 is a block diagram of the pulse shaping circuit of FIG. 2.

Although a number of lines symbols can be generated at the same time, for the sake of simplicity the following description relates to the generation of a single symbol.

In the schematic diagram of FIG. 1, a line symbol 1 is shown displayed on the screen 2 of a cathode ray tube. The screen is scanned by an interlaced field raster having even field lines 3 and odd field lines 3a. Typically the raster may be a 625 line, 50 Hz, raster, but for the sake of simplicity FIG. 1 shows a 12 line raster.

As can be seen from FIG. 1, the line symbol is made up of a series of brightened-up portions of the raster line. These brightened-up portions are produced by applying bright-up pulses to the brightness control cir-

cuitry of the cathode ray tube. For each brightened-up portion, it is necessary therefore to determine on which line of the raster the brightened-up portion is to occur (Y-coordinates) and at which points on the raster line the brightened-up portions are to begin and end (X-coordinates).

With a 625 line raster, 585 of the lines are visible, the remainder being hidden in field blank. The Y-resolution is therefore 1 in 585. To give an X-resolution comparable to the Y-resolution, each raster line must be divided into sufficient number of sections such that each section is equal to the distance between the raster lines. This number is equal to

15

$$585 \times \frac{4}{3} = 780$$

where 4/3 is the aspect ratio of the raster.

The basic parameters chosen to define a line are the central co-ordinates (X_c , Y_c) the length (L), the width (W) and the angle the line makes with the vertical (θ). From these parameters, the co-ordinates of the ends of the line are:

30

$$\begin{aligned} X_1 &= X_c - \frac{L}{2} \sin \theta \\ X_2 &= X_c + \frac{L}{2} \sin \theta \\ Y_1 &= Y_c - \frac{L}{2} \cos \theta \\ Y_2 &= Y_c + \frac{L}{2} \cos \theta \end{aligned} \quad (1)$$

35

As can be seen in FIG. 1, X_1 lies at the centre of the brightened-up portion having co-ordinate Y_1 . Therefore, X_{st} and X_{op} , the co-ordinates of the beginning and end of the brightened-up portion are given by

40

$$\begin{aligned} X_{st} &= X_1 - \frac{1}{2} W \sec \theta \\ X_{op} &= X_1 + \frac{1}{2} W \sec \theta \end{aligned} \quad (2)$$

45

The X co-ordinates for successive brightened-up portions increase by the same amount each time. This amount is called the increment and is equal to $h \tan \theta$ where h is the spacing between the raster lines. Thus, once X_{st} and X_{op} for the first line of the even field are known, X_{st} and X_{op} for succeeding lines of the even field can be found by successively adding twice the increment to the initial values of X_{st} and X_{op} . By adding once the increment to the initial values of X_{st} and X_{op} , the values of X_{st} and X_{op} for the first line of the odd field can be found and values of X_{st} and X_{op} for succeeding lines of the odd field can be found by successively adding twice the increment to the values of X_{st} and X_{op} for the first line of the odd field.

50

Thus, the only calculation necessary, once the values of X_{st} and X_{op} for the first brightened-up portion and the values of Y_1 and Y_2 have been calculated, is the successive addition of once or twice the increment to X_{st} and X_{op} .

55

Referring now to FIG. 2, the calculation of Y_1 , Y_2 , X_{st} , X_{op} and increment is carried out by a digital computer 10, and thus values of these quantities are in binary form.

60

As mentioned above, only 585 lines of the raster are visible. If the line symbol always started on an even field and finished on an odd field then the Y-co-

ordinates need only be of l in $292\frac{1}{2}$ resolution and a word length of 9 bits would be required to define Y_1 and Y_2 . However, to avoid the necessity of the line having to start and finish in this way, a further bit is added to the words to indicate whether or not the first or last (or both) bright-up pulses should be suppressed. The X resolution is 1 in 780 and therefore 10 bit words are required to define X_{st} and X_{op} .

As the X co-ordinate sections are equal to the raster line spacing h at $\theta = 0$, the increment is zero whereas at $\theta = 45^\circ$ the increment is equal to h . If the raster lines are considered to have unit spacing then at $\theta = 45^\circ$ the increment is 1. In this case the increment must be fractional for lines having θ between 0° and 45° , which implies that X_{st} and X_{op} must contain a fractional part.

Since, from equations (2)

$$X_{op} = X_{st} + w \sec \theta \quad (3)$$

this fractional part must be the same for successive values of X_{st} and X_{op} . Therefore, if the increment is split into two words inc and inc frac, each of 10 bits, lines having these angles can be drawn. For example, consider the situation where

$$\begin{aligned} X_{st} &= 100 \\ X_{op} &= 102 \\ \text{inc} &= 0 \\ \text{inc frac} &= 0.25 \quad (\theta = 14^\circ) \\ X_{frac} &= 0 \end{aligned}$$

Then for successive raster lines

$$\begin{aligned} X_{st} &= 100, X_{op} = 102 \quad X_{frac} = 0.25 \\ X_{st} &= 100, X_{op} = 102 \quad X_{frac} = 0.5 \\ X_{st} &= 100, X_{op} = 102 \quad X_{frac} = 0.75 \\ X_{st} &= 101, X_{op} = 103 \quad X_{frac} = 0.00 \\ X_{st} &= 101, X_{op} = 103 \quad X_{frac} = 0.25, \text{ etc.} \end{aligned}$$

On each line inc frac is added to X_{frac} and inc is added to X_{st} and X_{op} . On the line where X_{frac} overflows the carry is added to X_{st} and X_{op} . The binary output from the computer is fed to and stored in an output circuit 11 which is also fed by pulses from a cycle counter 12 in synchronism with the line scan. The cyclic counter 12 provides the division of the raster lines into X co-ordinate sections. To provide 780 sections per raster line, the frequency of the pulses must be $780 \times (1/52)$ US which equals 15 MHz. (52 US is the time of line scan). Coincidence between X_{st} and X_{op} and the relevant clock pulses causes the generation of a bright-up pulse which is fed to the brightness control of a cathode ray tube 13 through a delay circuit 14 and a pulse shaping circuit 15 or through the delay circuit 14 alone depending on the value of θ as explained below.

As the increment is added by the computer, the actual output therefrom involves only the current values of X_{st} and X_{op} . As shown in FIG. 3 these values are stored in respective output registers 16, 17. Each register has an associated comparator 18, 19 so that the value of X_{st} and X_{op} can be compared with the count from the cyclic counter 12. The outputs from the comparators 18, 19 are fed to a gate circuitry 20 which in response to the outputs develops a signal during the period when the output from the counter 12 is $\geq X_{st}$ and $\leq X_{op}$.

If $\theta = 45^\circ$, for every increment in X there is the same increment in Y (increment = 1) and the definition in X equals the definition in Y and a visually acceptable line is formed. However, for angles near the vertical (θ

small), for an increment in X there is a large number of increments in Y and the line appears stepped. For angles near the horizontal (θ large) the limit is in the Y direction and the line again appears stepped.

The stepped appearance of a near vertical line is due to the X position being limited by the number of steps along the raster line provided by the cyclic counter 12. The steps are most apparent when the increment is zero and inc frac is non-zero, i.e., at the point when X frac is carried over and X_{st} and X_{op} shift by one place which is approximately a 60ns shift. To overcome this problem the X definition needs to be increased and the pulses shifted according to X -frac. This could be done by increasing the pulse frequency but 15 MHz is the practical limit using standard components.

The solution adopted is to use delay circuitry and select the delay according to the value of X -frac. To increase the X -definition by a factor of 4 three 15 ns delay circuits 21, 22, 23 are used as shown in FIG. 4.

The outputs from the delay circuits are fed to a 4/1 multiplexer 24. The two most significant bits of X frac are applied by way of line 24a to data select lines of the multiplexer to select an appropriate delay. Thus, if

0	$\leq$	X_{frac}	< 0.25	No delay is selected
0.25	$\leq$	X_{frac}	< 0.5	15 ns delay is selected
0.5	$\leq$	X_{frac}	< 0.75	30 ns delay is selected
0.75	$\leq$	X_{frac}	< 1.00	45 ns delay is selected
0+1	$\leq$	X_{frac}	$< 0.25+1$	No delay is selected but as the value of X frac has overflowed, the position has been shifted by 60ns.

If even better X definition is required then seven $7\frac{1}{2}$ ns delay circuits or fifteen $3\frac{3}{4}$ ns delay circuits can be used with a corresponding increase in the number of bits of X frac applied to the data selection lines and replacement of the 4/1 multiplexer by an 8/1 or 16/1 multiplexer as appropriate. Generally, n delay circuits each having a delay x , and an $(n+1)/1$ multiplexer can be used, provided that $(n+1)x$ equals the cyclic counter pulse length.

The use of the delay technique means that the pulse frequency can be reduced if required, without losing the original definition. For example, seven 15 ns delay circuits and a frequency of $7\frac{1}{2}$ MHz gives an effective frequency of 60 MHz which is the same as if three 15 ns delay circuits and a 15 MHz frequency are used. Such a reduction in the pulse frequency has definite advantages particularly with regard to the output stage where X_{st} and X_{op} are compared with the output of the cyclic counter. As there is a reduction in the number of bits to be compared, a significant reduction in the amount of hardware is produced.

As can be seen from FIG. 1, for the width W to remain constant as the angle θ varies, the length of the bright-up pulse must vary. However, the increase in length of the sections defined by the cyclic counter at a reduced frequency means that the actual length of the bright-up pulse may not be the same as the right length to give a constant width line symbol.

To overcome this problem, a differential delay factor must be introduced; i.e., a bright-up pulse is delayed by different amounts at its rising and falling edges. This can be achieved as shown in FIG. 4, by introducing a 2/1 multiplexer 50 (shown dotted) so that the values of fractional values for X_{st} and X_{op} can be multiplexed on to the data select lines of the multiplexer 24. This

means that the computer must store the fractional values for X_{st} and X_{op} . However, the integer bits are fewer and accordingly, no penalty is incurred as regards storage requirements.

The stepped appearance of a near horizontal line is due to the limited number of raster lines on the screen. It is impractical to increase the number of raster lines and the disadvantage is overcome by shaping the bright-up pulses so that each brightened-up portion varies in brightness along its length and blends with the other brightened-up portions to give the illusion of a continuous line. FIG. 5A shows the optimum shape of the bright-up pulse. As the output pulses from the gate 20 (FIG. 3) are square with rise and fall times corresponding to the logic circuitry used, a further circuit, as shown in FIG. 6 is required for producing an approximation to this optimum shape. This approximation is shown in FIG. 5B. The leading and trailing edges of the pulse are formed by seven steps.

The pulse shaping circuit of FIG. 6 consists of a binary rate multiplier (BRM) 25 fed by pulses from the cyclic counter and having its output connected to the input of an up-down counter 26. Output signals from the counter 26 on lines 30-32 are fed to a 1 of 8 decoder 33. The output from the decoder 33 is fed to an non-linear digital to analogue converter 34 which has a non-linear characteristic of such terms as to control the bright-up circuitry of the tube so as to provide visually acceptable symbols.

The BRM 25 is a device which performs the function

$$\text{frequency out} = \frac{\text{frequency in } X \text{ } M}{64}$$

where M is a 6 bit number in the range 0-63. The frequency out is in fact a pulse rate which can be made repeatable using the clear facility on the BRM.

The up-down counter 26 is fed by the frequency out and counts at a rate determined by the frequency out.

The counter 26 begins counting at the beginning of the bright-up pulse, i.e., at X_{st} . The counting stops after seven counts and when X_{op} is reached the counter begins counting down to zero. The final output from the converter 34, which is applied to the brightness control is a pulse having leading and trailing edges formed of eight steps. The brightened-up portions of the raster thus have a brightness varying through eight shades of grey.

The control circuitry from the BRM 25 and the counter 26 consists of gates, A, B and C. The gates A, B receive the outputs from the output circuit gate 20 (FIG. 3) and from the lines 30-32 of the counter. The outputs from gates A and B form the input to gate C which has its output connected to the clear-enable facility of the BRM. Considering the output from the counter to be initially zero, the sequence of events is as follows:

i. At X_{st} , the gate A is enabled thus enabling the gate C and the BRM and the counter. When the counter reaches seven, the gate B is inhibited, thus inhibiting the gate C and clearing the BRM.

ii. At X_{op} , the gate B is enabled, thus enabling the gate C and the BRM and the counter again with the counter in the count-down state. When the counter

reaches zero, the gage A is inhibited, thus inhibiting the gate C and clearing the BRM.

It will be realised that as the pulse does not commence until X_{st} and has longer rise and fall times, the pulse as a whole will be later than it should be. A suitable correction is calculated by the computer to allow for this.

The technique described above only allows the use of graded bright-up pulses over angles of $\theta = +77^\circ$ to $+90^\circ$ and -77° to -90° . Outside these angles the appearance of the line is degraded. To overcome this, the influence of the BRM is extended by reducing the number of shades of grey to four. An extra bit of information added to the 6 bit word M, is required to define the different angle region. As the counter counts only to four, the significance of the count has to be doubled. This is achieved by the insertion of a 2/1 multiplexer 35 (shown dotted) before the 1 of 8 decoder. The control of the multiplexer uses the extra bit of information and 20 is switched for the duration of a bright-up pulse. The output of the multiplexer counts at twice the rate of the counter and hence the same peak value of the bright-up pulse is reached. The technique is used for angles of $74^\circ = 58^\circ$ to 77° and -58° to -77° .

25 Referring once more to FIG. 2, it can be seen that the delay circuit 14 and the pulse shpинг circuit 15 are in series, but that a switching circuit 60 allows the pulse shaping circuit to be by-passed.

As mentioned above, the pulse shaping technique is 30 only suitable for values of θ in the ranges 58° to 90° and -58° to -90° . For values of θ in the range -58° to $+58^\circ$, a further bit of information on X_{st} or X_{op} operates the switching circuit to bypass the pulse shaping circuit.

A final defect in the appearance of the line which 35 must be overcome is flicker at the beginning and end of the line.

Referring again to FIG. 1, it can be seen that the first part of the initial brightened-up portion and the last part on the final brightened-up portion are only drawn 40 on one field. This effect is particularly noticeable with a near horizontal line where these parts are quite long.

This effect is overcome by extending the length of the line at both ends and by generating a blanking signal outside the required length. The flickering regions thus lie in the blanked off parts.

From the above description, it is apparent that in order to draw a line symbol the current values of X_{st} and X_{op} have to be incremented line by line to give the new values. Hence, computation must be carried out 50 on every raster line between Y1 and Y2. The obvious time to carry out this computation is during line blanks. However, this period is only 12 us long whereas the period of line scan is 52 us long. Therefore, by carrying out the computation for a particular raster line in the 55 previous line scan and storing the values in the output registers during line blank, four times as many line symbols that can be drawn is thus dependent on how many computations the computer can carry out in 52 us.

60 We claim:

1. Display apparatus in which the display comprises a raster of parallel lines and a symbol is displayed by changing a visual parameter of one or more selected portions of the raster lines comprising:

65 a. cyclic digital counter means operating in synchronism with the raster line scan so that successive counts of the counter correspond to successive sec-

- tions of each raster line, thereby notionally dividing each raster line into sections respectively corresponding to different counts of the counter;
- b. means for producing digital outputs defining the position of each raster line portion required to be selected to display a required symbol, in accordance with the notional numbering of sections of the raster lines effected by the counter means;
- c. an output circuit comprising means for comparing said digital output with the output of the counter means to produce an output signal for changing said visual parameter when there is correspondence between said digital outputs and the output of the counter means; and
- d. delay means connectable to delay the output of said output circuit by a fraction of the period between successive counts of the counter means when a said digital output fractionally exceeds the corresponding count of the digital counter by a predetermined amount, thereby to effectively increase the number of sections into which each raster line is notionally divided.
2. Display apparatus according to claim 1, in which the output circuit comprises means for comparing the digital outputs defining the beginning and end of the selected raster portion with the output of the cyclic counter and for developing an output signal during the period when the output from the counter is greater than or equal to the digital output defining the beginning and less than or equal to the digital output defining the end, of the selected raster portion.
3. Display apparatus according to claim 1 wherein said delay means includes a number of equal length

15

20

25

30

delay circuits arranged to produce delays of $0, x, 2x \dots nx$ (where n is the number of delay circuits, x is the delay of each delay circuit and $(n + 1)x$ equals the period between successive counts of the counting means); and an $(n + 1)$ multiplexer for selecting an appropriate delay according to the amount by which a said digital output exceeds the output of the digital counter.

4. Display apparatus according to claim 3 wherein said digital outputs define the beginning and end of each said raster line portion required to be selected, and said output circuit comprises means for producing an output signal when the digital counter output is greater than or equal to the digital output defining the beginning, and less than or equal to the digital output defining the end of a said raster line portion.

5. Display apparatus according to claim 4 wherein said delay means comprises means for delaying the beginning and end of the output signal of the output circuit by different amounts.

6. Display apparatus according to claim 1 including pulse shaping means for shaping the output of the output circuit so that the degree of change in the visual parameter varies along the length of a said raster line portion.

7. Display apparatus according to claim 6, in which the shaping means comprises circuitry for producing a signal having stepped leading and trailing edges.

8. Display apparatus according to claim 7, including means for varying the number of steps forming the leading and trailing edges of the signal in dependence on the angle the desired symbol makes with the raster lines.
